Primary Examiner — Clint A Samuel(57) **CLAIM**

The ornamental design for an LED display screen, as shown and described.

DESCRIPTION

FIG. 1 is a bottom, front and left side perspective view of an LED display screen showing our new design;
 FIG. 2 is a top, rear and right side perspective view thereof;
 FIG. 3 is a front elevational view thereof;
 FIG. 4 is a rear elevational view thereof;
 FIG. 5 is a left side view thereof;
 FIG. 6 is a right side view thereof;
 FIG. 7 is a top plan view thereof;
 FIG. 8 is a bottom plan view thereof;
 FIG. 9 is an enlarged view of portion 9 in FIG. 1;
 FIG. 10 is an enlarged view of portion 10 in FIG. 1; and,
 FIG. 11 is an enlarged view of portion 11 in FIG. 2.
 The broken lines in the drawings illustrate portions of the LED display screen which form no part of the claimed design.

1 Claim, 11 Drawing Sheets(56)
